UNITED STATES PATENT OFFICE.

JOHN J. LYTH, OF VALLEYFIELD, QUEBEC, CANADA.

DRIER.

Application filed March 10, 1924. Serial No. 698,229.

To all whom it may concern:

Be it known that I, JOHN J. LYTH, a subject of the King of Great Britain, and resident of the city of Valleyfield, in the Province of Quebec and Dominion of Canada, have invented certain new and useful Improvements in Driers, of which the following is a full, clear, and exact description.

This invention relates to apparatus for drying material in strip or ribbon form such as cloth, paper and the like where it is not desirable to have the material in contact with the drying element.

The apparatus at present used for drying cloth in certain stages of manufacture comprises a series of hollow plates arranged vertically in closely spaced relation and heated by passing steam into them. The cloth is led up and down between the plates but out of contact therewith. For various reasons these plate driers are expensive to install and owing to their construction cannot be repaired in ordinary mills, so that expensive delays are occasioned by waiting for fresh plates to be received. Furthermore, plate driers have the disadvantage that moisture driven out of the cloth is held in close contact with the cloth by the plates and can escape only at the edges of the plates. A mechanical disadvantage of the closely spaced plates is that thick portions in the cloth, occasioned by sewing the ends of two pieces together, frequently stick between the plates causing the cloth to tear.

One of the objects, therefore, of this invention is to provide a drier which may be easily and cheaply manufactured and which may be repaired easily and quickly in the mill.

Another of the objects is to provide a drier so constructed that the moisture driven out of cloth may escape from contact with the cloth.

A further object is to provide a drier so constructed that, while the spacing of the cloth from the drier elements is not greater than usual, there is nevertheless ample room for passage of seams through the drier without danger of tearing the cloth.

A still further object is to provide a drier of increased efficiency.

Additional objects and advantages may be ascertained from the following description and from the accompanying drawings.

According to the invention the drier is

composed of two sections each comprising a plurality of connected headers carrying parallel tubes. The headers of each section are connected together side by side so as to provide a block of parallel tubes arranged in widely spaced vertical and closely spaced horizontal rows. The two sections are assembled so that the tubes are staggered. The spacing is such that narrow vertical 60 passages are left between the vertical tube rows of the combined sections for the passages of the cloth.

In the accompanying drawings, which illustrate one embodiment of the invention:

Fig. 1 is a side elevation of the drier.

Fig. 2 is a plan view of the same.

Fig. 3 is an end elevation of one section of the drier, partly in vertical section and illustrating in broken lines the positions 75 that will be occupied by the tubes of the complementary section, and also illustrating the manner of passing cloth through the drier.

Fig. 4 is a side elevation of a unit showing 80 an alternative form of tube and alternative form of unit connection.

Fig. 5 is a fragmentary detail further illustrating the form of unit connection.

Referring more particularly to the drawings, 85 11 designates a plurality of similar headers, preferably of cast iron and of any suitable cross-section, which, for convenience of description, has been shown as square. Each header is provided on opposite sides, 90 near the ends, with faced annular bosses 12 surrounding openings 13 communicating with the interior of the header. A boss 14 is formed on each end of the header and is adapted to be tapped for attachment of 95 steam inlet and outlet pipes. On one of the remaining sides of the header a boss or bosses 15 are provided and tapped for insertion of a plurality of closely spaced pipes 16 which are arranged in parallelism and 100 perpendicular to the header. The free ends of these pipes are closed by plugs or welding. On the remaining side of the header a suitable number of supporting lugs 17 are provided. It will be understood that the provision of the bosses 14 and 15 is merely a 105 matter of common practice to provide strength locally and that they are not essential to the invention.

It will further be understood that if desired two sorts of headers 110 may be used, the one adapted for connection to circulating pipes and having end bosses

14, and the other not adapted for such connection and not having bosses.

Each header with its attached pipes 16 constitutes a drier unit. As many units as desired are assembled to form a drier section. The assembly is accomplished by placing the headers side by side with their faced lugs 12 in abutting relation. Rods 18 are then passed through all sections at top and bottom and secured by caps or blind nuts 19 which serve to bind the units together and also to close the outer openings 13 of the outer headers. It will be understood that the invention is not confined to the structural features described for assembly as any other usual method of assembling radiator sections may be employed. One or more headers of each section is tapped in its top and bottom bosses 14 for connection of the steam inlet pipe 20 and condensate outlet pipe 21. When the units are assembled into a section the tubes will be in vertical and horizontal rows, the vertical rows being spaced somewhat more than twice the diameter of a tube apart, center to center and the horizontal rows somewhat more than the diameter of a tube apart.

Two sections are assembled to complete the drier in such a manner that the vertical tube rows interdigitate, leaving narrow vertical passages between. One section is set slightly lower than the other (by suitable positioning of supports 22 on which the sections hang by engagement of the lugs 17 with the supports), so that the tubes of the combined sections are in staggered arrangement, as clearly shown in Figures 1 and 3.

The drier is placed between the usual upper and lower rolls 23 which lead the cloth up and down, the rolls being of proper size and location to keep the cloth in the middle of each vertical passage between the tube rows and thus out of contact with the tubes.

Instead of the rods 18 which connect all sections together, the bosses 12 may be provided with slotted lugs 24 (Figures 4 and 5) into which bolts 25 may be dropped to connect the units individually to one another and to enable any unit to be removed from a section without breaking all the joints in the section as is the case when common connecting means, such as the rods 18, are used. Preferably these lugs project in the longitudinal direction of the headers and are preferably disposed at diametrically opposite points of the bosses in order that pressure may be uniformly distributed in the joints when the fastenings are tightened. While bolts have been shown, it will be understood that any other suitable form of fastening may be substituted.

When in use, the tubes are heated by condensation of steam therein and radiate this heat to the cloth passing between them.

Owing to the staggered arrangement each tube is opposite the space between tubes of adjacent rows, so that moisture driven out of the cloth in passing each tube can escape from close contact with the cloth into the spaces between tubes of the adjacent row. While the straight passages between the vertical tube rows are very narrow or restricted, as in existing plate driers, it will be readily seen from Figure 3 that, owing to the staggered arrangement of the tubes, much wider or less restricted tortuous passages also exist. When a thick seam in the cloth is passing through the drier it can follow the tortuous passages with very little resistance to movement and without danger of tearing the cloth. The heating surface of the tubes is greater than the heating surface of plates in a drier of the same overall dimensions and thus more than compensates for the reduced area of heated surface in closest proximity to the cloth, so that cloth may be passed more rapidly through a tube drier than through a plate drier of equal size or conversely a smaller tube drier will suffice if the speed of the cloth is not increased.

Various modifications are possible without departing from the spirit of the invention; for example, the tubes may be U-shaped as shown in Figure 4.

Having thus described my invention, what I claim is:

1. A drier comprising a pair of similar sections each composed of a series of multtube units, the units of the two sections interdigitating and defining narrow passages.

2. A drier comprising a pair of similar sections each composed of a series of connected units, each unit including a header and a plurality of tubes connected thereto, the units of the two sections interdigitating and defining narrow passages.

3. A drier comprising a pair of multtube sections, the tubes of each section being arranged in spaced rows and the rows of the two sections interdigitating.

4. A drier comprising a pair of multtube sections, the tubes of the two sections interdigitating and being arranged in staggered relation and defining restricted straight passages.

5. A drier comprising a series of tubes in staggered arrangement defining restricted straight passages extending in one direction only and occupying parallel planes.

6. A drier comprising a series of tubes in staggered arrangement defining narrow straight passages and wider tortuous passages coinciding in part with the straight passages, said straight passages extending in one direction only and occupying parallel planes.

7. A drier comprising a pair of multtube sections having the tubes thereof arranged

- in rows perpendicular to one another, the rows in one direction being spaced a little more than twice the diameter of a tube and the rows in the other direction being spaced a little more than the diameter of a tube, and means to so support the sections that the widely spaced tube rows thereof interdigitate and the tubes assume a staggered relation.
- 10 8. A drier comprising a series of units each including a header and a series of tubes, each tube being connected at one end to the header and being closed at the other end.
- 15 9. A drier comprising a series of tubes arranged in closely spaced rows in one direction, and providing narrow passages between the rows for movement of a sheet to be dried, the tubes being in staggered relation to provide opposite any tube a space for escape of moisture from the sheet to be dried.
- 20 10. A drier for material in sheet form, comprising a series of drying elements arranged in rows and between which the sheet material passes, said drying elements being disposed to heat any part of the moving sheet alternately on opposite sides and to provide moisture escape passages on the opposite side of the sheet from each of 30 said drying elements.
11. A drier comprising a plurality of sections, mutually engaging annular bosses on said sections for bringing the sections into communication with one another, and means 35 for connecting the sections, slotted lugs on the section bosses and fastening means engageable in the lug slots.
12. A drier comprising tubes arranged in spaced parallel rows, the tubes of adjacent 40 rows being in staggered relation whereby tortuous passages are formed between the tube rows, the spacing of the tube rows being such that clear straight passages are formed between adjacent tube rows and 45 contained within the tortuous passages and of less width than the tortuous passages.
- In witness whereof, I have hereunto set my hand.
- JOHN J. LYTH.
